St. Ann, and Grant E. Knoblauch, St. Louis, Mo., assignors to Artercraft Venetian Blind Manufacturing Company of St. Louis, St. Louis, Mo., a corporation of Missouri

Filed Aug. 15, 1958, Ser. No. 52,223

Term of patent 14 years

(Cl. D21—6)

FIGURE 3 is an enlarged detail of the upper side portion of the awning to illustrate the relative prominence of the corrugated strip that is parallel to the roof.

We claim:

The ornamental design for a rigid window awning substantially as shown and described.
